UNITED STATES PATENT OFFICE.

OLIVER P. MEGAHAN, OF WESTERVILLE, OHIO.

INSULATOR-SUPPORT.

1,295,918.

Specification of Letters Patent.

Patented Mar. 4, 1919.

Application filed October 19, 1918. Serial No. 258,916.

To all whom it may concern:

Be it known that I, OLIVER P. MEGAHAN, a citizen of the United States, residing at Westerville, in the county of Franklin and State of Ohio, have invented a certain new and useful Improvement in Insulator-Supports, of which the following is a specification.

This invention relates to the type of insulator support or cross arm shown and described in the Letters Patent of the United States issued to me January 5, 1915, No. 1,123,342, and the object of the present invention is to simplify the construction of such devices and render them more easily manufactured. Another object of the invention is to render such a construction less likely to permit leakage of the electricity should a line become detached and sag or fall on it.

The invention is embodied in the details of construction shown in the example depicted in the accompanying drawings, set forth in the following description and finally claimed.

In said drawings—

Figure 1 is a longitudinal section of the outer shell.

Fig. 2 is a transverse section, on a larger scale, of said outer shell.

Fig. 3 is a plan view of a fraction of the outer shell looking at the filling or under side thereof.

Fig. 4 is a combined sectional and perspective view of a fraction of the outer shell in position to be filled with concrete.

Fig. 5 is a perspective view of a fraction of the curved bar or strip used to retain the filling of concrete supplied to the shell.

Fig. 6 is a transverse section of the insulator support showing its filled or completed condition.

Fig. 7 is a diagrammatic view of the sheet metal as cut before being formed into the outer shell.

The metallic outer shell is cut, pressed or bent out of sheet metal to form a hollow trough-like body with a curved top 5, sloping sides 6, lips 7, and closing ends 9, the last being substantially as in my said former

patent. The curved top is formed with longitudinal openings leaving bridges at 10. The lips 7 are slit to form tongues 11 that are bent down and become embedded in the filling of concrete subsequently supplied. It will be observed that the lips 7 are flat and not curved as in my former construction. The advantage of the present construction is that the hollow body is more easily supplied with the cement to and flush with the lips. To fill the sheet metal shell it is placed in inverted position in holders 12 but to form a bottom to prevent the escape of the material through the openings I insert in the holders 12 a transversely curved bar 13. Said bar 13 on its concave side molds the material that constitutes the top of the insulator support or cross arm. Before supplying the cement I put in place iron pins 14 which form the holes for the reception of the shanks of the glass or porcelain insulators. In filling the sheet metal shell, as thus described and arranged, I first spread along the bottom a quantity of pulverized glass or other insulating material of a depth sufficient to make a stout layer. After this I pour in the usual concrete mixture of sand, cement and water to entirely fill the shell. The water, more or less charged with cement drains from said mixture into the pulverized glass and constitutes not only the binder for the glass but the means of connecting the glass layer to the body of concrete. In filling the metallic shell suitable reinforcing bars, such as shown at 15 can be placed in position to be embedded in the concrete. After the filling as thus described has hardened and dried the cross arm is ready for attachment to the pole and to receive the usual glass or porcelain insulators in the usual manner.

The structure thus formed makes a durable cross arm with the cement portion thoroughly protected from the rapid disintegrating effects of weather. The shells and shanks can be transported at small cost to distant points and the glass and concrete supplied near the place of use of the finished cross arm.

The forms and proportions of the parts can be varied without departing from the gist of the invention as claimed.

What I claim is:

- 5 1. An insulator support including a sheet metal shell and a filling of concrete, said shell having an opening at its upper portion

and a filling of insulating material exposed at said opening.

2. An insulator support including a body 10 of concrete having its upper edge of insulating material molded integral therewith, substantially as described.

OLIVER P. MEGAHAN.
